TENSIOMETER

Gerhard P. Lessmann, Forest Hills, and Paul C. Lottes, Wilkinsburg, Pa., assignors to Westinghouse Electric & Manufacturing Company, East Pittsburgh, Pa., a corporation of Pennsylvania

Application January 15, 1941, Serial No. 374,506

10 Claims. (Cl. 265—1.6)

Our invention relates, generally, to tensiometers, and, more particularly, to tensioning devices and indicating means for subjecting a strip of material to tension and indicating the degree of strip tension as the strip passes between adjacent work devices.

In the operation of steel strip rolling mills, it is common practice to subject the strip to tension as it extends between adjacent roll stands and/or between a roll stand and an adjacent roll by causing a tensioning roller to bear against and apply a transverse force to the strip.

Such tensioning rollers are usually arranged to be actuated by a single operating device which rigidly connects the two end bearings of the tensioning roller and thereby imparts the same movement to both ends of the tensioning roller. Means are also commonly provided for causing the strip tension to vary with the strip deflection so that the strip deflection is a measure of the strip tension. Such a tensioning device is shown in the copending application of G. P. Lessmann, Serial No. 252,934, filed January 26, 1939, now Patent No. 2,250,540, issued July 29, 1941.

Differences in the screw-down settings of the two ends of the reducing rolls results in a difference of strip reduction from one side of the strip to the other, and, even though the desired total tension may be applied to the strip, all or most of the tension may be applied to one side of the strip and there may be such an unbalance of the strip tension as to tear the strip at the point where the greatest tension is applied.

An object of our invention is to provide a strip tensioning and tension indicating device which shall function to indicate the total strip tension and the tension differential between the two sides of the strip, which shall function to limit the tension differential to predetermined adjustable amounts, which shall be simple in construction, and simple and efficient in operation.

These and other objects and advantages of the invention will be apparent from the following detailed description taken in connection with the accompanying drawings, in which:

Figure 1 is a front elevation view, partly in section, of a tensiometer embodying the principal features of our invention.

Fig. 2 is a side elevation view of the indicator actuating mechanism associated with the tensiometer of Fig. 1.

Fig. 3 is a front elevation view of the mechanism shown in Fig. 2.

Fig. 4 is a sectional view taken along the line IV—IV of Fig. 1.

Fig. 5 is an elevation view, partly in section, of an adjustable relative displacement limiting coupling which is a part of the mechanism of Fig. 1.

Fig. 6 is a sectional view of the bearing mounting for the end of the tensioning roller of Fig. 1.

Fig. 7 is a diagrammatic representation of an indicating system associated with the tensiometer of Fig. 1.

Figs. 8 and 9 are sectional views on the lines VIII and IX of Fig. 1.

In practicing the invention, a tension roller 10 has its ends rotatably mounted on supporting members 12 and 14 which are pivotally mounted and actuated by power units 16 and 18 to cause the tensioning roller to apply a transverse force to the strip as it extends between adjacent roll stands of a strip rolling mill or between a roll stand and an adjacent reel to thus subject the strip to tension. Spherical bearing members, a sectional view of one of which is shown in Fig. 6, and disposed between the ends of the tensioning roller and the supporting members 12 and 14 to permit freedom of independent movement of the separate ends of the tensioning roller 10.

The strip deflecting movements of the separate ends of the tensioning roller 10 are transmitted to a shaft 20 and a sleeve 22 concentric therewith, respectively, and these movements are transmitted by the shaft and sleeve to an indicator actuating mechanism 24 disposed in a casing 26. The indicator actuating mechanism 24 functions to actuate remote indicator actuating means such as synchro-tie transmitters in accordance with the differential between the deflections of the two side portions of the strip by the tensioning roller and the sum of the deflections of the two side portions of the strip.

An adjustable coupling 28 disposed between the shaft 20 and the sleeve 22 functions to limit the differential between the degrees of deflection of the two edge portions of the strip.

A remote indication system shown diagrammatically in Fig. 7 functions to give an indication at a suitable remote point of the differential between the deflections of the two edge portions of the strip and the sum of the deflections of the two edge portions of the strip.

The operating parts of the tensioning device are mounted on bracket members 30 and 32 which are connected by a beam member 34 and which are adjustably mounted on the housings 36 and 38 of a strip rolling mill or other work device.

Considering the invention more in detail, the ends of the tension roller 10 are supported by their respective supporting members 12 and 14 by spherical bearings, the details of the bearing associated with the supporting member 14 being shown in Fig. 6. The bearing may comprise an outer bearing member 40 having an inner spherical bearing surface cooperating with a spherical bearing surface on the outer race 42 of a roller bearing unit. The rollers 44 of the bearing unit engage the outer race 42 and the inner race 46, the inner race being attached to the end member 48 of the tension roller 10. The bearings are held in place on the supporting members 12 and 14 by means of cap members 50 and 52 as shown in Figs. 1 and 4.

The sleeve member 22 and the shaft 20 are rotatably supported on bracket members 54 and 56 which, in turn, are secured in any suitable manner to the bracket members 38 and 32. The sleeve member 22 may be fixedly secured to the roller supporting member 14 in any suitable manner such as by a key member 15 as shown in Fig. 8 so that the movement of the supporting member 14 by the power unit 18 will cause rotational movement of the sleeve member 22. Likewise, the shaft 20 may be secured by a key member 13 to the supporting member 12 to provide rotational movement of the shaft 20 when the supporting member 12 is actuated by the power unit 16.

The power units 16 and 18, a section of one of which is shown in Fig. 1, may comprise a cylinder member 58 having an extension 60 which extends into a slot in the supporting member 14 and is pivotally attached thereto by a pin member 62. The cylinder member 58 is actuated by a coil spring 64 which reacts against a piston 66 mounted upon a tubular piston stem 68 which extends through a cover member 70 of the cylinder 58. The piston stem 68 has bearing members 72 and 74 secured thereto by any suitable means such as by welding and these bearing members cooperate with knife edge bearing members 76 and 78 to support the piston stem on the shelf portion 80 of the bracket 32. A damping cylinder 82 is secured to an extension of the piston stem 68 and has a piston member therein operated by a piston stem 84 secured to the cylinder 58 and operating in a damping fluid to prevent too rapid motion of the tensioning roller.

The sleeve member 22 and the shaft 20 extend into the casing 26, as indicated in Figs. 2 and 3. An arm member 86 having a rack segment 88 secured thereto is secured to the shaft 20 for rotation therewith. An arm member 90 is secured to the sleeve member 22 for rotation therewith and has a shelf member 92 attached thereto. A motion transmitting device such as a synchro-tie transmitter 94 is mounted upon the shelf member 92 and has a shaft 96 upon which there is mounted a pinion 98 in cooperative relation with the rack segment 88. A second rack segment 100 is mounted upon the arm member 86. A third arm member 102 is rotatably mounted upon the sleeve member 22 and has a rack segment 104 thereon. A shaft member 106 is rotatably mounted on the arm 90 and has mounted thereon gear members 108 and 110 cooperatively engaging the rack segments 100 and 104, respectively, the diameter of the gear members 108 and 110 having the ratio of 2 to 1. A motion transmitting device 112 is mounted on the bracket 32 by a bracket 114 and is operatively con-

nected to the rack segment 104 by means of a shaft member 116 and a gear member 118 which engages the rack segment 104.

The motion transmitting devices 94 and 112 may be synchro-tie transmitters which are commonly known in the art connected with receiving units 120 and 122, respectively, which may be synchro-tie receiver units and which operate indicator devices 124 and 126, respectively.

In the operation of the device, the spring member 64 exerts an upward force upon the operating arms 12 and 14 to cause the tensioning roller 10 to bear against a strip of material as it extends between adjacent work devices such as adjacent strip rolling mill stands, or a strip rolling mill stand and an adjacent reel, to thus subject the strip to tension. The tension to which the strip is subjected will be a function of the position of the tensioning roller 10 and the differential between the tension on the two edge portions of the strip, will cause different deflections of the two edge portions of the strip by the tension roller 10. The deflections of the two edge portions of the strip are a function of the angular displacement of the shaft 20 and the sleeve member 22 which are transmitted to the indicator actuating mechanism 24.

The rotation of the shaft 20 will cause the arm 86 to rotate carrying with it the rack segment 88 and transmitting its movement to the pinion 98. The rotation of the sleeve 22 in the same direction will cause the arm 90 to rotate in the same direction carrying with it the pinion 98 causing the pinion to rotate in the opposite direction to the rotation caused by the movement of the rack 88 by the shaft 20. Thus the pinion 98 and the position transmitting device 94 operated thereby will assume a position which is a measure of the relative angular displacements of the shaft 20 and the sleeve 22 and the indication transmitted by the position transmitting device 94 to the instrument 124 will be a function of the differential tension across the width of the strip which is acted upon by the tension roller 10. The scale of the indicating device 124 may accordingly be graduated in strip tension and the differential strip tension may be read directly therefrom.

The rotation of the shaft 20 will cause the rack segment 100 to drive the gear member 108 which, in turn, will drive the gear member 110 and the gear member 110 will rotate the arm 102 through its engagement with the rack segment 104. As the arm member 90 is rotated by the sleeve 22, it will carry with it both of the gear members 108 and 110 thus causing further displacement of the arm 102 by the engagement of the gear member 110 with the rack segment 104 and the movement of the shaft 106 with the arm 90.

Thus it will be seen that, with the ratio of the diameters of the gears 108 and 110 equal to 2 to 1, equal angular displacements of the arms 86 and 90 will cause equal displacements of the arm 102 and that the displacement of the arm 102 will be proportional to the algebraic sum of the angular displacements of the arms 86 and 90.

Thus the movement of the arm 102 will be proportional to the sum of the angular displacements of the shaft 20 and the sleeve 22 and this movement will be transmitted through the gear member 118 and the motion transmitting device 112 to the indicator 126 which may be graduated to

indicate the total tension on the strip which is acted upon by tensioning roller 10.

The adjustable coupling 28, as shown in Fig. 5, is provided to limit the relative displacement of the shaft 20 with respect to the sleeve 22 and comprises a sleeve member 128 secured to the shaft 20 by any suitable means such as a key 130 and having substantially V-shaped indentations 132 in one edge thereof. A sleeve member 134 having protuberances 136 extending into and shaped similar to the indentations 132 is mounted for rotation with the sleeve member 22 by a key member 138. It will be seen that the allowable relative angular displacement between the shaft 20 and the sleeve 22 is controlled by the circumferential spacing of the edge portions 139 and 140 of the sleeve members 134 and 128 respectively, and that this spacing may be adjusted by axially moving the sleeve member 134. The axial movement of the sleeve member 134 is provided by a collar member 141 threaded upon the sleeve 22 and coupled with the sleeve member 134 by means of a collar 142 which has sliding engagement with circumferential slots in the sleeve member 134 and the collar member 141. A second collar member 144 serves as a locking member for the collar member 141 to prevent rotation thereof. Thus as the collar member 141 is rotated by its threaded engagement with the sleeve member 22, it will cause the axial movement of the sleeve member 134 to vary the spacing between the surfaces 139 and 140 to thus vary the limit of the relative angular displacement of the sleeve member 22 in the shaft 20. A suitable cover 146 for the adjustable tube 28 is secured to the sleeve member 128.

The tensioning device may be adjusted vertically by a mechanism which comprises brackets 148 and 150 secured to the mill housings 36 and 38 from which there are suspended bolt members 152 and 154 which extend through bracket members 156 and 158 which are, in turn, secured to the bracket members 39 and 32. Members 160 and 162 bear upon the brackets 156 and 158 and threadedly engage the bolt members 152 and 154 and may be rotated by a handwheel 164 by means of worms 166 and 168 which are operated by the handwheel 164 and which engage worm gears 170 and 172. The worm gears 170 and 172 are secured to and rotate the members 160 and 162. After the device has been adjusted by the handwheel 164, the brackets 30 and 32 are clamped to the mill housings 36 and 38 by means of bolts 174, 176, 178 and 180 which are secured to the mill housings and extend through slots in the brackets 30 and 32. A gauge is provided for indicating the vertical position of the tensioning device and comprises a gauge scale 182 secured to the mill housing 36 by means of a bracket 184 and cooperating with a mark 186 on the bracket 30 to indicate the relative position of the bracket 30 and the mill housing 36.

Thus it will be seen that we have provided a tensioning device for a strip rolling mill which shall function to subject the two edge portions of a strip to tension in accordance with the strip deflections and which shall function to indicate the total tension on the strip and the tension differential between the two edge portions of the strip.

In compliance with the requirements of the patent statutes, we have shown and described herein the preferred embodiment of our invention. It is to be understood, however, that the invention is not limited to the precise construc-

tion shown and described but is capable of modification by one skilled in the art, the embodiment herein shown being merely illustrative of the principles of our invention.

5 We claim as our invention:

1. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, means rotatably mounting said sleeve member in a position displaced from and substantially parallel with said roller, a shaft member substantially concentric with and extending beyond said sleeve member, means securing one of said supporting arms to said sleeve member for rotation therewith, means securing said other supporting arm to said shaft for rotation therewith, separate means for actuating said supporting arms to thereby cause said tensioning roller to apply a transverse deflecting force to the strip and indicating means actuated by said sleeve member and said shaft.

2. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, means rotatably mounting said sleeve member in a position displaced from and substantially parallel with said roller, a shaft member substantially concentric with and extending beyond said sleeve member, means securing one of said supporting arms to said sleeve member for rotation therewith, means securing said other supporting arm to said shaft for rotation therewith, separate means for actuating said supporting arms to thereby cause said tensioning roller to apply a transverse deflecting force to the strip, said actuating means comprising means for varying the strip tension as a function of the degree of deflection of the strip and indicating means actuated by said sleeve member and said shaft.

3. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, a shaft member, means rotatably mounting said shaft member in a position displaced from the tensioning roller and substantially concentric with and extending beyond said sleeve member, means securing one of said supporting arms to said sleeve member for rotation therewith, means securing said other supporting arm to said shaft member for rotation therewith, and separate means for actuating said supporting arms to thereby cause said tensioning roller to apply a transverse deflecting force to the strip, said actuating means comprising means for varying the strip tension as a function of the degree of deflection of the strip, and means responsive to the degree of rotation of said sleeve member and said shaft member for automatically determining the total strip tension and the tension

differential between the two edge portions of the strip.

4. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, means rotatably mounting said sleeve member in a position displaced from and substantially parallel with said roller, a shaft member substantially concentric with and extending beyond said sleeve member, means securing one of said supporting arms to said sleeve member for rotation therewith, means securing said other supporting arm to said shaft member for rotation therewith, separate means for actuating said supporting arms to thereby cause said tensioning roller to apply a transverse deflecting force to the strip, and means responsive to the degree of rotation of said sleeve member and said shaft member for automatically determining the sum of the deflections and the difference between the deflections of the two edge portions of the strip.

5. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, means rotatably mounting said sleeve member in a position displaced from and substantially parallel with said roller, a shaft member substantially concentric with and extending beyond said sleeve member, means securing one of said supporting arms to said sleeve member for rotation therewith, means securing said other supporting arm to said shaft member for rotation therewith, separate means for actuating said supporting arms to thereby cause said tensioning roller to apply a transverse deflecting force to the strip, and means responsive to the degree of rotation of said sleeve member and said shaft member for automatically determining the sum of the deflections and the difference between the deflections of the two edge portions of the strip, said deflection determining means comprising a first arm member and a second arm member secured to said shaft member and said sleeve member respectively for rotation therewith, a first rack member secured to one of said arm members, a first gear member rotatably mounted upon the other arm member and disposed to operatively engage said rack member, a third arm member, means mounting said third arm member for rotation concentric with said shaft member and said sleeve member, a second rack member secured to said third arm member, a pair of gear members rotatably mounted on said other arm member in driving relation with each other and each disposed in operative engagement with a different one of said rack members, means responsive to the movement of said first gear member for indicating the differential between the deflections of the two edge portions of the strip, and means responsive to the movement of said third arm member for indicating the sum of the deflections of the two edge portions of the strip.

6. In a device for tensioning a strip of material as it extends between adjacent work devices, a

tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, a shaft member, means rotatably mounting said shaft member in a position displaced from said roller and substantially concentric with and extending beyond said sleeve member, means securing one of said supporting arms to said sleeve member for rotation therewith, means securing said other supporting arm to said shaft member for rotation therewith, separate means for actuating said supporting arms to thereby cause said tensioning roller to apply a transverse deflecting force to the strip, said actuating means comprising means for varying the strip tension as a function of the degree of deflection of the strip, and means responsive to the degree of rotation of said sleeve member and said shaft member for automatically determining the total strip tension and the tension differential between the two edge portions of the strip, said tension determining means comprising a first arm member and a second arm member secured to said shaft member and said sleeve member respectively for rotation therewith, a first rack member secured to one of said arm members, a first gear member rotatably mounted upon the other arm member and disposed to operatively engage said rack member, a third arm member, means mounting said third arm member for rotation concentric with said shaft member and said sleeve member, a second rack member secured to said third arm member, a pair of gear members rotatably mounted on said other arm member in driving relation with each other and each disposed in operative engagement with a different one of said rack members, means responsive to movement of said first gear member for indicating the differential between the tensions on the two edge portions of the strip, and means responsive to the movement of said third arm for indicating the sum of the tensions on the two edge portions of the strip.

7. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, means rotatably mounting said sleeve member in a position displaced from and substantially parallel with said roller, a shaft member substantially concentric with and extending beyond said sleeve member, means securing one of said supporting arms to said sleeve member for rotation therewith, means securing said other supporting arm to said shaft member for rotation therewith, separate means for actuating said supporting arms to thereby cause said tensioning roller to apply a transverse deflecting force to the strip, and means responsive to the degree of rotation of said sleeve member and said shaft member for automatically determining the sum of the deflections and the difference between the deflections of the two edge portions of the strip, said deflection determining means comprising a first arm member and a second arm member secured to said shaft member and said sleeve member respectively for rotation therewith, a first rack member secured to one of said arm members, a first gear member rotatably mounted upon the other arm member and disposed to operatively engage said rack member, a third arm member, means mounting said third arm member for rotation concentric with said shaft member and said sleeve member, a second rack member secured to said third arm member, a pair of gear members rotatably mounted on said other arm member in driving relation with each other and each disposed in operative engagement with a different one of said rack members, means responsive to the movement of said first gear member for indicating the differential between the deflections of the two edge portions of the strip, and means responsive to the movement of said third arm member for indicating the sum of the deflections of the two edge portions of the strip.

to one of said arm members, a first gear member rotatably mounted upon the other arm member and disposed to operatively engage said rack member, a third arm member, means mounting said third arm member for rotation concentric with said shaft member and said sleeve member, a second rack member secured to said third arm member, a pair of gear members rotatably mounted on said other arm member in driving relation with each other and each disposed in operative engagement with a different one of said rack members, a first electrical position transmitting device mounted on said other arm member and connected in operative relation with said first gear member, a second electrical position transmitting device disposed to be operated by said third arm member, first and second electrical position receiving means connected in cooperative circuit relation with said first and second electrical position transmitting devices, and indicating means actuated by said first and second receiving means for indicating the differential between the deflections of the two edge portions of the strip and the sum of the deflections of the two edge portions of the strip respectively.

8. In a device for tensioning a strip of material as it extends between adjacent work devices, a tensioning roller disposed to bear against the strip and thus subject it to tension by deflecting it from the line between the work devices, a supporting arm adjacent each end of said tensioning roller, means rotatably mounting each end of the tensioning roller on its adjacent supporting arm, a sleeve member, a shaft member, means rotatably mounting said shaft member in a position displaced from the roller and substantially concentric with and extending beyond said sleeve member, means securing one of said supporting arms to said sleeve member for rotation therewith, means securing said other supporting arm to said shaft member for rotation therewith, separate means for actuating said supporting arms to thereby cause said tensioning roller to apply a transverse deflecting force to the strip, said actuating means comprising means for varying the strip tension as a function of the degree of deflection of the strip, and means responsive to the degree of rotation of said sleeve member and said shaft member for automatically determining the total strip tension and the tension differential between the two edge portions of the strip, said tension determining means comprising a first arm member and a second arm member secured to said shaft member and said sleeve member respectively for rotation therewith, a first rack member secured to one of said arm members, a first gear member rotatably mounted upon the other arm member and disposed to operatively engage said rack member, a third arm member, means mounting said third arm member for rotation concentric with said shaft member and said sleeve member, a second rack member secured to said third arm

member, a pair of gear members rotatably mounted on said other arm member in driving relation with each other and each disposed in operative engagement with a different one of said rack members, a first electrical position transmitting device mounted on said other arm member and connected in operative relation with said first gear member, a second electrical position transmitting device disposed to be operated by said third arm, first and second electrical position receiving means connected in cooperative circuit relation with said first and second electrical position transmitting devices, and indicating means actuated by said first and second receiving means for indicating the differential between the tensions on the two edge portions of the strip, and the sum of the tensions on the two edge portions of the strip respectively.

9. In a device for tensioning a strip of material as it extends between adjacent work devices, a tensioning roller disposed to bear against the strip and subject it to tension by deflecting it from the line between the work devices, separate actuating means for moving each end of said tensioning roller to cause the tensioning roller to apply a transverse deflecting force to the strip, and mutually cooperating stop means mounted upon the separate actuating means and so disposed as to limit the strip deflecting motion of either end of the tensioning roller with respect to the other end to thereby limit the deflection differential between the two edge portions of the strip to predetermined adjustable amounts.
10. In a device for tensioning a strip of material as it extends between adjacent work devices, a tensioning roller disposed to bear against the strip and thus subject it to tension by deflecting it from the line between the work devices, two separate rigid support members each disposed adjacent a different end of said tensioning roller and each mounted adjacent one end thereof for independent rotational movement about a common axis, means rotatably mounting each end of said roller on its adjacent support member intermediate the ends thereof, separate actuating means pivotally attached to the free ends of the support members for rotating each of said support members about the common axis to thereby cause said tensioning roller to apply a transverse deflecting force to the strip, said actuating means comprising means for varying the strip tension as a function of the degree of deflection of the strip, and means including electrical position transmitting apparatus mechanically actuated by the support members and in accordance with the relative rotational movements thereof and electrical position receiving apparatus responsive thereto for indicating the difference in the degree of deflection of the two side edges of the strip to thereby measure the tension differential between said two side edges.
